UNITED STATES PATENT OFFICE

MAY HURD KRUEGER, OF CLEVELAND, OHIO.

DESIGN FOR A FLAG, PENNANT, SIGN, EMBLEM, OR AN ARTICLE OF A SIMILAR NATURE.

53,130.

Specification for Design.

Patented Mar. 25, 1919.

Application filed August 16, 1918. Serial No. 250,255. Term of patent 7 years.

To all whom it may concern:

Be it known that I, MAY HURD KRUEGER, a citizen of the United States, residing in Cleveland, in the county of Cuyahoga and State of Ohio, have invented a new, original, and ornamental Design for Flags, Pennants, Signs, Emblems, or Articles of a Similar Nature, of which the following is a specification, reference being had to the accompanying drawing, forming part thereof.

The figure is an elevation of a pennant, showing my new design.

The pennant consists of a central field of red, upon which are displayed two white bars, said field being surrounded by a blue border.

I claim:

The ornamental design for a flag, pennant, sign, emblem, or an article of a similar nature, as shown.

Signed by me this 23rd day of July, 1918.

MAY HURD KRUEGER.
